ELECTRICALLY HEATED STEAM IRON

Edward J. Wiggins, Chicago, Ill., assignor to Jack Galter, Chicago, Ill.

Application December 18, 1939, Serial No. 309,751

4 Claims. (Cl. 38—77)

This invention relates to an electrically heated steam iron for use in ironing clothes, pressing washed goods and for other similar purposes.

Among the objects of this invention is to provide a construction that will stop water in the iron from entering the steam chamber adjacent the steam receiving pipe so as to prevent water from passing out the discharge openings. Another object is to create an electrically heated steam iron having a steam expansion chamber adjacent the discharge openings, and to provide in combination therewith enlarged openings for the passage of an increased supply of wet steam. My invention also contemplates such other objects, advantages and capabilities as will later more fully appear and which are inherently possessed by my invention.

While I have shown in the accompanying drawing a preferred form of my invention, yet I wish it understood that the same is susceptible of modification and change without departing from the spirit of my invention.

Referring to the drawing, Fig. 1 is a side elevational view of my iron with portions broken away to show the interior; Fig. 2 is a top plan view with the handle plate removed; Fig. 3 is a rear elevational view with a portion broken away as shown on line 3—3 of Fig. 1; Fig. 4 is a bottom plan view of the shoe plate; Fig. 5 is a plan view of the inner surface of the shoe plate; Fig. 6 is an enlarged detail sectional view of the expansion chamber as shown on line 6—6 of Fig. 1.

The embodiment selected to illustrate my invention comprises a shoe plate 10 having a smooth outer bottom ironing or pressing surface 11 and a body member 12 attached to said shoe plate 10 by suitable means such as screws 13. The bottom of the body member 12 has a slight depression 14 to which is attached an electrical element 15. A corresponding depression 16 is also provided in the inner and upper portion of the shoe plate 10 to accommodate the electrical element 15 when the body member 12 is attached to the shoe plate 10.

The body member 12 is hollow so as to provide a water chamber 17. At the upper front portion of the interior of the body member 12 is a steam chamber 18 extending from about the middle upper portion of the body member 12 forwardly under the dome portion 19. The rear wall 20 of the steam chamber 18 has an opening 21 to receive steam rising from the water chamber 17.

The floor 35 of the steam chamber 18 has an aperture 36.

The outer top 22 of the body member 12 has a

recess 23 with an indented flange 24 to receive the handle plate 25. Screws 26 attach the handle plate 25 to the flange 24. A handle 27 is attached to the handle plate 25.

In steam chamber 18 immediately forward of opening 36 is a substantially semicircular baffle member 54 extending across the width of the steam chamber, with its inner curved surface facing the rear wall 20. The lower end of the baffle member 54 contacts the floor 35 of steam chamber 18 but the upper end of the baffle member does not contact the bottom of the handle plate 25, thereby leaving a steam passageway 55 therebetween. The upper end of the baffle member 54 is directly above opening 36 in the floor 35. The baffle member 54 thus forms an anteroom 56 in the steam chamber 18.

In use when water, because of boiling, sloshing or otherwise, enters the anteroom 56, it strikes the inner surface of the baffle member 54 and is thrown by a somersault movement caused by the curve of the baffle member out of the anteroom through opening 21 in the rear wall 20 back into the water chamber 17. Water that does not reach opening 21 in the rear wall will drop out through opening 36 in the floor 35.

The baffle member 54 does not interfere with the passage of the superheated steam because the steam passes through passageway 55 into the forward part of the steam chamber 18.

It will be noted that steam chamber 18 continues under dome portion 19, where it passes up into the top opening of a steam receiving pipe 37 which passes diagonally downwardly through an opening 38 in the front bottom portion of the body member 12.

The steam conduit 37 discharges the steam into an expansion chamber 57 formed by a recess 58 in the shoe plate 10. A modification of my expansion chamber is to provide for a communicating cut-out portion 59 in the lower bottom surface of the toe of the body member 12, the cut-out portion 59 forming one expansion chamber within the recess 58. The expansion chamber 57 has a guide portion 60 leading the steam to a depression 61 in the shoe plate 10 in which are located a plurality of spaced extra large steam discharge openings 62.

Having thus described my invention, I claim:

1. An electrically heated steam iron comprising a shoe plate having an outer ironing surface and steam discharge openings, a hollow body member attached to said shoe plate, an electrical element having means for connection with an electrical source of supply, said electrical element positioned

- between said shoe plate and said body member, said body member having a water chamber and means for the reception of water for said water chamber, a steam chamber formed within said hollow body member above the water chamber, said steam chamber having an opening to receive steam formed in the water chamber, said steam chamber having a floor and a top, a forwardly curved substantially semi-circular baffle member 5 extending across said steam chamber and adapted by its curved surface to somersault water entering through the opening in the steam chamber back through the opening in the steam chamber to the water chamber, said baffle member extending 10 upwardly from the floor of the steam chamber and ending short of contact with the top of the steam chamber so as to leave a space therebetween for the passage of steam to the upper portion of the steam chamber, a steam conduit 15 with its upper end in the steam chamber and its lower end communicating with said steam discharge openings in the shoe plate, and a handle attached to said body member.
2. In an electrically heated steam iron, a body member having a hollow interior providing space for a water chamber, a steam chamber positioned in said hollow interior of the body member above the water chamber, said steam chamber having an opening to receive steam formed in the water 20 chamber, said steam chamber having a floor and a top, a forwardly curved substantially semi-circular baffle member extending across said steam chamber and adapted by its curved surface to somersault water entering through the opening in the steam chamber back through the opening in the steam chamber to the water chamber, said baffle member extending 25 upwardly from the floor of the steam chamber and ending short of contact with the top of the steam chamber so as to leave a space therebetween for the passage of steam to the upper portion of the steam chamber.
3. An electrically heated steam iron comprising a bottom member having an outer ironing surface and a plurality of steam discharge openings, a body member having a water chamber, said body member attached to said bottom member, means for electrically heating said iron and forming steam out of the water in the water chamber, a steam chamber having walls and a floor, said steam chamber formed within said body member above said water chamber, said steam chamber having an opening in one of its walls to re-

ceive steam formed in the water chamber, a forwardly curved substantially semi-circular baffle member extending across the width of the steam chamber and adapted to stop water entering through the opening in the steam chamber from passing farther into the steam chamber and by its curved surface to return the water through the opening in the steam chamber back into the water chamber, said baffle member extending upwardly from the floor of the steam chamber and ending short of contact with the top of the steam chamber so as to leave a passageway therebetween for the passing of steam farther into the steam chamber, and a steam conduit with its upper end in the forward portion of the steam chamber, and its lower end communicating with the steam discharge openings in the ironing surface of the bottom member.

4. An electrically heated steam iron comprising a bottom member having an outer ironing surface and a plurality of steam discharge openings, a body member having a water chamber, said body member attached to said bottom member, means for electrically heating said iron and forming steam out of the water in the water chamber, a steam chamber having a rear wall, a floor and a top, said steam chamber formed within said body member above said water chamber, said steam chamber having an opening in its rear wall and an opening in its floor, a forwardly curved substantially semi-circular baffle member extending across the width of the steam chamber and forming an anteroom, the lower end of the baffle member contacting the floor of the steam chamber immediately forward of the opening in said floor, the upper end of the baffle member extending above and over said opening in the floor of the steam chamber, said baffle member adapted to stop water entering the anteroom from passing into the front portion of the steam chamber and by its curved surface to return the water through the openings in the rear wall and floor of the anteroom of the steam chamber back into the water chamber, said baffle member ending short of contact with the top of the steam chamber so as to leave a space therebetween for the passage of steam into the front portion of the steam chamber, and a steam conduit with its upper end in the front portion of the steam chamber, and its lower end communicating with the steam discharge openings in the ironing surface of the bottom member.

EDWARD J. WIGGINS.
